Atty.

UNITED STATES PATENT OFFICE.

WALLACE C. BROWN, OF MONSON, MAINE.

DERRICK-SWINGER.

SPECIFICATION forming part of Letters Patent No. 257,149, dated May 2, 1882.

Application filed March 6, 1882. (No model.)

To all whom it may concern:

Be it known that I, WALLACE C. BROWN, a citizen of the United States, residing at Monson, in the county of Piscataquis and State 5 of Maine, have invented certain new and useful Improvements in Derrick-Swingers; and I do hereby declare the following to be a full, clear, and exact description of the invention, such as will enable others skilled in the art to 10 to which it appertains to make and use the same, reference being had to the accompanying drawings, and to letters or figures of reference marked thereon, which form a part of this specification.

My invention relates to an improvement by 15 which the swinging or turning of a derrick or hoisting-crane can be effected. I attain that object by the mechanism illustrated in the accompanying drawings, in which—

Figure 1 is an elevation of so much of a derrick or crane as is necessary to illustrate my invention. Fig. 2 is a horizontal section on line $\alpha\alpha$ of Fig. 1.

Similar letters refer to similar parts throughout the several views.

The frame by means of which the derrick and rotating devices are supported may be constructed in any approved manner and of the necessary strength. In the drawings it consists of the vertical pieces A A and horizontal pieces A' A² A³ and cross-braces.

F is a shaft having a bearing in pieces A' A² of the frame, being secured by the boxings f f.

Keyed or otherwise secured to the upper end of the shaft F is a pinion, a. This pinion 35 meshes with a horizontal spur-wheel, b, which is secured to derrick-post B and turns with it. Derrick-post B is stepped pivotally in the frame, either in the upper part, A², as shown in Fig. 1, or, passing through the upper part, may be 40 pivoted in the foundation upon which the frame rests. Derrick-post B is also pivoted at its upper end, and is supported by guys or in any other approved manner.

The hoisting mechanism of the derrick is not 45 shown in the drawings, as it is not essential to my invention.

G is a shaft mounted horizontally in pieces A A of the frame in the same vertical plane with shaft F. It is secured by boxings g g, 50 and has mounted upon it the belt-pulley C, to which the power is applied to rotate the shaft G. Upon the shaft G are also mounted beveled friction-wheels D D'.

On the lower end of shaft F, and between

the friction-wheels D D', is mounted a beveled 55 friction-wheel, E, adapted to be engaged alternately with wheels D D', or disengaged from both of them, by oscillating the lower end of shaft F in the vertical plane of the axis of the shaft G, the upper boxing, f, being arranged 60 to permit such limited oscillation. The lower end of shaft F has its bearing upon a block, I, which slides longitudinally upon the horizontal piece A' of the main frame. The block I slides in the straps or ways i i, which pass 65 around it and are secured to the piece A'. The reciprocation of the block I is effected by the lever L, which is pivoted in the cross piece A' and oscillates horizontally, having a slotted bearing in the block I, so that the oscillation 70 of the lever L reciprocates the block I.

To the piece A of the frame is pivoted the hand-lever M, as shown in Fig. 1, which oscillates vertically, and by which the block I is reciprocated by means of a link, L', which connects the oscillating end of the lever L to the lower end of the hand-lever M.

When it is desired to rotate the derrick the friction-wheel E is, by means of the hand-lever M, thrown into engagement with that one of the moving wheels D D' (say D', as shown in the drawings) which will rotate it in the required direction. After rotating the derrick to the required position the friction-wheels can be disengaged and the movement stopped. To 85 rotate the derrick in the opposite direction the wheel E is brought into engagement with the wheel D.

In place of friction-wheels, beveled-gear wheels may be used.

What I claim as my invention, and desire to 90 secure by Letters Patent, is—

The combination, with a rotary derrick-post, B, having mounted thereon the gear-wheel b, and the continuously-rotating power-shaft G, 95 carrying the friction-wheels D D', of the swinging shaft F, having the friction-wheel E, adapted to engage with either of the wheels D D', and pinion a, meshing directly with the gear-wheel b on the derrick-post, substantially as shown 100 and described.

In testimony whereof I affix my signature in presence of two witnesses.

WALLACE C. BROWN.
